Primary Examiner — Caron D Veynar*Assistant Examiner* — Mehri Bajoul(74) *Attorney, Agent, or Firm* — Loza & Loza, LLP;
Heidi L. Eisenhut(57) **CLAIM**

The ornamental design for an exercise band with tether, as shown and described.

DESCRIPTION

FIG. 1 is a front top left side perspective of an exercise band with tether of the present invention;

FIG. 2 is a front elevation view of the exercise band with tether of FIG. 1;

FIG. 3 is a rear elevation view of the exercise band with tether of FIG. 1;

FIG. 4 is a right side elevation view of the exercise band with tether of FIG. 1;

FIG. 5 is a left side elevation view of the exercise band with tether of FIG. 1;

FIG. 6 is a top plan view of the exercise band with tether of FIG. 1; and,

FIG. 7 is a bottom plan view of the exercise band with tether of FIG. 1.

In the drawings, the evenly broken lines represent stitching and forms part of the claimed design while all other broken lines directed to environmental subject matter only and form no part of the claimed design.

1 Claim, 4 Drawing Sheets(56)
